ELECTROPIANO

Winsor D. White, Jr., Blowing Rock, N.C., assignor to
D. H. Baldwin Company, Cincinnati, Ohio

Filed Apr. 21, 1971, Ser. No. 136,295

Term of patent 14 years

Int. Cl. D17—01

U.S. Cl. D56—9

FIG. 1

FIG. 4

FIG. 2**FIG. 3**FIG. 1 is an angular perspective view of an electro-piano embodying my new design.

FIG. 2 is a front elevational view thereof.

FIG. 3 is a side elevational view thereof.

FIG. 4 is a fragmentary cross sectional view taken along the section line 4—4 in FIG. 1.

The back of the electropiano (not shown) is conventional. The shading of the lower front board indicates a vertically pleated and ribbed fabric panel and is partially omitted in FIG. 2 for convenience in illustration.

I claim:

The ornamental design for an electropiano, substantially as shown and described.
